Miss Mason Fenwick Lawrence,

Attorneys.

UNITED STATES PATENT OFFICE.

GEORGE W. SPAHR, OF MECHANICSBURG, PENNSYLVANIA.

COMBINATION HEADREST AND SERVER.

Application filed June 5, 1922. Serial No. 565,903.

To all whom it may concern:

Be it known that I, GEORGE W. SPAHR, a citizen of the United States, residing at Mechanicsburg, in the county of Cumberland and State of Pennsylvania, have invented certain new and useful Improvements in Combination Headrests and Servers; and I do hereby declare the following to be a full, clear, and exact description of the invention, such as will enable others skilled in the art to which it appertains to make and use the same.

This invention relates to an improved head rest and server for use on barbers' chairs and has for its object to provide a mechanism which will automatically serve or feed a clean portion of paper over the head rest after the latter has been used by a customer. The improved device embodies means for automatically holding certain movable parts of the mechanism in a given position to prevent accidental operation of the serving mechanism until such time as it is desired that the serving mechanism shall function.

The above and other novel features of the invention will appear from the detailed description taken in connection with the two sheets of drawings forming part of this specification.

Referring to the drawings,

Figure 1 is a side elevation of the improved head rest and server showing the same as attached to the back of a barber's chair;

Fig. 2 is a rear elevation of the same;

Fig. 3 is a section taken on line 3—3 of Fig. 2;

Fig. 4 is a section taken on line 4—4 of Fig. 2;

Fig. 5 is a section through the mechanism for operating and controlling the rotation of the roll which serves to unwind the paper from its spool, and

Fig. 6 is a view showing the position of the automatic locking means when the head rest is in substantially upright or out-of-use position.

In the drawings, 10 designates the adjustable bar which projects upwardly from the back of the barber's chair and to which the head rest is adapted to be removably secured by means of a socket 11 which projects downwardly from a cross piece 12

which at its terminal ends is pivotally secured as at 13 to the side walls 14 of the head rest. It will now be understood that the head rest is turnably mounted with respect to the socket 11, the pivotal mounting 13 being at the lower rear corner of the head rest which, as shown in the drawings, is of general rectangular form in side elevation.

Extending upwardly from the cross piece 12 to the socket 11 is a plate 15 which serves among other things, as a partial closer for the back of the head rest. This plate is secured to the cross piece in any suitable manner as by screws 15'.

Mounted on plate 15 is a U-shaped catch 16 and mounted on one wall 14 is a weighted hook or latch 17 which is adapted to interlock with the hook 16 in certain positions of the head rest, (see Fig. 4). Members 16 and 17 may be termed an automatic locking device and the purpose of the same will presently appear.

Mounted on the other wall 14 is a case 18 within which is contained mechanism for controlling rotational movement of a rubber roller 19 between which and a rubber roller 20, the serving paper 21 is adapted to pass, the paper being mounted on a spool 22 at the other end of the head rest frame, it being understood that the paper leads from the spool 22 over a padded cushion 23 on the front face of the head rest frame. Upon turning of the rubber roller, paper is drawn from the spool over the head pad 23. At this point it may be stated that roller 20 is yieldingly mounted with respect to roller 19, there being a spring 20' which tends to move the roller 20 into frictional engagement with roller 19. To allow for relative displacement of roller 20, the axle ends 20^a of the same are mounted in slots 20^b in the walls 14 (see Fig. 1). As shown, the spring 20' re-acts against one of the cross rods 14' which serve to maintain the walls 14 in spaced, rigid relation.

The mechanism within the case 18 will now be described. Referring to Fig. 5, it will be seen that the case is provided with a guide-way 24 within which is mounted a slide or bar 25. The front of this bar is provided with rack teeth 26 and the back thereof with ratchet teeth 27. Disposed at right angles to the guide-way 24 is a com-

municating guide-way within which is mounted a slideable ratchet tooth 28 which is adapted to interlock with the ratchet teeth 27. Mounted in a passage at the lower 5 end of the case 18 is a cam lever 29. The upper end of this lever is suitably connected to the ratchet tooth 28 so as to move the latter out of contact with the teeth 27 on the bar 25. Secured to the casing 18 is a leaf 10 spring 30 which is adapted to bear against the spring tooth 28 to force the same into engagement with the teeth 27 on the bar 25. The end of the slideable tooth 28 in engagement with the spring is preferably 15 beveled as at 28' in order to lower the contact point with the spring. The lower end of the cam lever 29 is provided with a toe 31 which is adapted to engage with a contact piece 32 mounted on the plate 15 (see 20 Fig. 3).

Referring to Fig. 3, it will now be seen that when the plate 15 is moved in the direction of the arrow *a*, the contact piece 32 will co-act with the toe 31 to swing the 25 cam lever in a direction away from the cross piece 12. This movement of the lever will serve to disengage the ratchet tooth plate 28 from the teeth 27 on the bar 25 for a purpose that will presently appear. 30 Extending laterally from the slide 25 is a shelf 33 which forms a seat for an expansion spring 34 which at its other end reacts against a bracket 35 secured to the case 18. The spring is compressed by inward 35 movement of the plate 15 which carries a post 36 which is screw-threaded with the plate. Adjustment of this post determines the amount of paper that is served by controlling the displacement of the rack bar 40 33. The energy stored up in the spring will serve to rotate the roll 19 when the plate 15 is moved to operate the trip or lever 29.

When the barber's chair is tilted the 45 weight of the head of the occupant serves to automatically set the server as shown in Figs. 3 and 4. In this position the latch 17' interlocks with the hook 16 to prevent accidental outward movement of the plate 50 15. The center of gravity of the hook 17, in said position, is such as to maintain the parts 16 and 17 in interlocked relation. When the chair is brought to normal position, the latch 17 becomes disengaged from 55 the hook 16, whereupon the trip 29 is rocked on its pivot 29' by movement of the plate 15 in direction of arrow *a* to release the spring 34 to rotate the roll 19 for the purpose specified. Thereafter the plate 15 is locked 60 by the gravity latch 17 against inward movement by the heel 17' thereof seating in the seat 16' in the hook member 16.

Extending between the plates 14 is a shaft 65 37 on which is fixed a pinion 38, said pinion being in engagement with the rack 26 on

the bar 25. At the other end of the shaft is fixed a ratchet wheel 39 and loose on the shaft adjacent the wheel 39 is a gear 40 which carries a pawl 41 adapted to engage with the teeth on the ratchet wheel 39. The gear wheel 40 is in mesh with a pinion 42 fixed on the shaft on which the roller 19 is mounted. It will now be understood that when the slide or bar 25 is moved upwardly against the tension of the spring 34 by the plate 15 that the shaft 37 carrying the ratchet wheel will be rotated in a counter-clockwise direction as viewed in Fig. 4. When the spring 34 functions to move the slide 25 downward the shaft 37 will be 70 positively coupled to the gear 40 whereupon rotation will be imparted to the roller 19. Inasmuch as the paper is frictionally held against the roller 19 by the spring-pressed roller 20, a certain length of paper will 75 be unrolled from the spool 22 when rotation is imparted to the roller 19.

At one corner of the head rest frame is mounted a shield 43 which, at its lower edge, is serrated to facilitate the severance of the paper which has passed between the rollers 19 and 20. The head rest pad 23 is mounted on a hinged cover plate 44, the plate being hinged at the upper end of the frame as at 45 to permit the cover plate to be lifted so as to expose the roll of paper at the lower end of the frame. The lower end of the cover plate may be provided with a finger hold 44' and the sides of said plate may project downwardly on the outside of the walls 14. In Fig. 1, the flange is shown as 80 cut away at the upper corner in order to clear the exposed end of the plate-spacing rod 14'.

The roll of paper 22 may be supported in any suitable manner at the lower end of the head rest frame. In the present instance, there is provided a cylinder 46 which has a slot 47 through which the paper 21 is passed, the upper part of the cylinder being cut away to permit replacing of the roll within the cylinder. The cylinder is secured to the walls 14 of the frame in any suitable manner.

In order to permit the manual drawing 100 of the paper across the pad 23, the roller 19 is provided with a knurled thumb wheel 19' at one of its ends (see Fig. 2).

The operation of the device will now be 105 briefly described. The normal position of the improved head rest will be substantially as shown in Fig. 1, that is to say, slightly inclined to the vertical. The barber, preparatory to shaving a customer, tilts the 110 chair backward until the head rest assumes the position shown in Figs. 3 or 4. The head of the occupant is now resting on the pad 23 and the weight of the head is sufficient to rock the head frame about the axis 13 of the cross bar 12 which is secured to the 115 120 125 130

socket 11 which latter is telescoped over the post 10 which rises from the back of the barber's chair. As the head rest frame is rocked in the manner just stated the latch 5 17 engages with the hook 16, thereby preventing accidental upward movement of the head rest frame while the barber's chair is in an inclined position. Relative movement between the plate 15 and the walls 14 also 10 serves to set the mechanism within the case 18, the spring 34 being compressed. The compression movement of the spring is without effect on the roller 19. When the barber's chair is brought to normal position as 15 in Fig. 1, the latch 17 drops away from the hook 16 and the spring 34 thereupon causes the plate 15 to move outwardly relatively to the plate 14. This upward movement is accompanied by movement of the bar or 20 slide 25 and hence rotational movement is imparted to the roller 19 through the train of gears in connection therewith as will be readily understood.

It will now be seen that a fresh piece of 25 paper is brought in position over the pad 23 immediately after the barber's chair has been brought to normal position and that the head rest is, therefore, always in sanitary condition as regards the serving paper. The 30 portion of paper which has passed between the rollers 19 and 20 may be torn off and used as a lather paper for the following customer.

The present invention is an improvement 35 on my Letters Patent No. 1,217,652, patented February 27, 1917.

While I have described the mechanism with considerable particularity of detail, I 40 desire it to be distinctly understood that no limitations on the invention are intended except as may be imposed by the appended claims.

What I claim is:

1. In a head rest, the combination of a 45 support adapted for attachment to a barber's chair, a tiltable frame mounted thereon, a roller, a spring motor for operating said roller, a gravity lock between the support and frame preventing relative movement therebetween except at selected positions, and means tripping the spring motor for operation when the gravity lock permits the said relative movement.

2. In a head rest, the combination of a 50 support adapted for attachment to a barber's chair, a tiltable frame mounted thereon, a roller, a spring motor for operating said roller, a gravity lock between the support and frame preventing relative movement therebetween except at selected positions, and a cam lever to be tripped to release the spring motor by relative movement of the support and frame.

3. In a head rest, the combination of a 55 support adapted for attachment to a bar-

ber's chair, a tiltable frame mounted thereon, a roller, a spring motor for operating said roller, a gravity lock between the support and frame preventing relative movement therebetween except at selected positions, said spring motor including a trip to release the spring motor for operation, and means carried by the support for tripping the trip. 70

4. In a head rest, the combination of a 75 support adapted for attachment to a barber's chair, a tiltable frame mounted thereon, a roller, a spring motor for operating said roller, a gravity lock between the support and frame preventing relative movement therebetween except at selected positions, said spring motor including a pawl-operating lever, and means carried by the support for moving the lever. 80

5. In a head rest, the combination of a 85 support, a tiltable frame mounted thereon, a spring motor attached to said frame, a roller operable by said motor, a lever projecting from the motor case, a lever-tripping cam-finger carried by said support. 90

6. In a head rest, the combination of a 95 support, a tiltable frame mounted thereon, a paper holder at the lower end of the frame, a roller at the other end of the frame for unwinding paper from a roll of the same held by the said holder, a spring motor for turning said roller in one direction, and means operable by relative movement of the support and frame for tripping the motor mechanism to turn the roller. 100

7. In a head rest, the combination of a support, a tiltable frame mounted thereon, a paper holder at the lower end of the frame, a roller at the other end of the frame for unwinding paper from a roll of the same held by the said holder, a spring motor for turning said roller in one direction, means 105 operable by relative movement of the support and frame for tripping the motor mechanism to turn the roller, and a gravity operated lock for preventing relative movement of the frame and support except at selected points. 110

8. In a head rest, the combination of a support, a tiltable frame mounted thereon, a paper holder at one end of the frame, a roller at the other end of the frame for unwinding paper from a roll in the said holder, a spring motor for turning said roller in one direction, means operable by relative movement of the support and frame for tripping the motor mechanism to turn the roller, and a pad-carrying cover hinged to said frame at the roller end of the frame. 115

9. In a head rest, the combination of a support, a frame pivoted thereon, a paper holder at one end of the frame, a roller at the other end of the frame, a spring motor for operating the roller in one direction, means carried by the support for tripping 120

the motor for operation, and a gravity operated lock for controlling the tripping mechanism.

10. In a head rest, the combination of a support, a frame pivoted thereon, a spring motor secured to the frame, said motor comprising a case, a rack bar slidable in said case, a catch for locking said bar against

movement in one direction, a lever for moving said catch, means on the support for moving said lever, a roller turnable by said motor and gravity operated means for controlling the movement of the lever. 10

In testimony whereof I affix my signature.

GEORGE W. SPAHR.
